UNITED STATES PATENT OFFICE

FRED R. KALCK, OF PHILADELPHIA, PENNSYLVANIA

CLOCK MECHANISM

Application filed March 16, 1927, Serial No. 175,722. Renewed April 28, 1930.

My invention has reference to clock mechanisms with which an illuminating medium is associated so that a plurality of clock dials bearing ornamental decorations, pictorial displays or advertisements may be successively brought into alignment with the time-indicating elements and clearly exhibited. The present invention embodies improvements on the mechanism covered by 10 Theriault Patent No. 1,275,791, dated Aug. 13, 1918, as more fully hereinafter set forth.

In the drawing—

Fig. 1 is a front view of the mechanism with certain parts removed and broken away 15 to better show the improved mechanism;

Fig. 2 is a sectional view on the line 2—2 of Fig. 1;

Fig. 3 is a side elevation of the mechanism partly in section;

Fig. 4 is a detail side elevation of one of the trains of gearing.

Referring to the annexed drawing by reference-characters, 5 designates a minute-hand mounted upon a cylinder 6 and extending radially into the hollow arbor formed by said cylinder and other parts hereinafter mentioned. This minute-hand cylinder 6 carries a gear 7 which meshes with a gear 8 driven by the clock mechanism 9 of the usual type. Affixed to the gear 8 is a pinion 10 which drives a gear 11 carrying the hour-hand 12, this gear 11 being journalled on a plurality of pins 13 projecting inwardly from the frame part 14.

The cylinder 6 is journalled on similarly-spaced pins 15 carried by said frame piece 14. The foregoing parts are covered by a casing-ring 16 fastened to the front frame-plate 14. It will be observed that it is important that the two hands 5 and 12 shall be as close to the dial transparencies 36 (hereinafter described) as is possible, in order to get as clear an image or shadow thereof on the screen as possible. In order

45 to bring these hands to this desirable position, the support for the minute-hand 5 extends outwardly through the ring-casing 16, while the supporting-rod 12' of the hour-hand 12 must be extended radially inwardly 50 and then forwardly through not only the

gear 11 but the whole in the frame 14 and also through the gear-ring 6.

For the purpose of setting the clock-hands, the wheels 8 and 10 are frictionally mounted on a shaft 17 of the clock-works, 55 a manually-operable setting gear 18 being arranged to be meshed with gear 8. Affixed to the shaft 17 is a supplemental gear 19 which drives a train of gearing consisting of a pinion 20, gear 21, pinion 22 and gear 23, the gears 20 and 21 being removably mounted on a plate 24 by means of a removable screw journal-pin 25. The gear 22 is also removably mounted on plate 24 by a removable screw journal-pin 26. The gear 23 is affixed to a shaft 27 by means of a screw 28. The shaft 27 is driven by a train of clock gearing connected with spring 29. The screw 28 also affixes to shaft 27 a pallet-wheel 30 having a plurality of spaced pallet-fingers 31 arranged in a circle and projecting forwardly. The plate 24 is pivotally mounted on the shaft 27 so that it may be swung on a center coincident with the axis of said shaft, and to hold this plate 75 in its adjusted position, I provide it with an arcuate slot 32 and employ in connection therewith a thumb-nut 33. With this mechanism, it will be observed that the spring 29 tends to drive the gear 23 with its pallet-wheel 30 in the direction of the arrow shown on said wheel 23, and the train of gearing 19—20—21—22, being under the control of the clock mechanism, serves to time the said pallet-wheel 30. By thus driving the pallet-wheel 30 by means of a separate spring-actuated train of gearing, the work of driving the same is taken off the clock mechanism proper.

The advertisements are carried by disk 90 34 affixed to a shaft 35, these advertisements being, as formerly, carried by transparent clock-dials 36 so positioned on the wheel that they successively register with the hollow arbor in which the hour and minute 95 hands operate. Affixed to the shaft carrying the advertising-wheel 34 is a companion pallet-wheel 37 having pallet-fingers 38 extending inwardly toward the front frame member 14, the two pallet-wheels being 100

overlapped at their adjacent rims so that the pallet-fingers of the larger wheel 37 will pass through the openings between the pallet-fingers of the smaller wheel 30. The shaft carrying the pallet-wheel 37 and the advertising-disk is rotated by a train of gearing actuated by a clock-spring 39. One of the fingers 38 normally rests against the exterior face of one of the pallet-fingers 31 and slides along thereon until it registers with one of the openings between said fingers 31, whereupon it jumps across the pallet-wheel 30 and strikes against the inner face of one of the opposite fingers 31, whereupon it rides until it can pass away from wheel 30 through one of the spaces between the fingers 31. When the finger finally passes away from wheel 30, the next finger 38 on the disk 37 comes into action by striking against the outer surface of the next pallet-finger 31, whereupon the operation is repeated. In this way, the clock-dial-carrying disk 34 is intermittently rotated, the intervals of rest being determined entirely by the speed of rotation of the smaller pallet-wheel 30. These intervals may be varied in length of time by varying the ratio of the gears in the train of gearing 20—21—22—23, all of these gears being mounted on a support which is adapted to be moved to a position where a new set of gear-wheels may be substituted. It will be observed that the train of gearing 20, etc., is not employed for driving the pallet-wheel 30, but simply for the purpose of regulating the speed thereof; the work of driving the pallet-wheel 30 is performed by spring 29.

The formation of the hollow arbor in my present mechanism is advantageous over the hollow arbor structure shown in the aforesaid patent in that it is simpler to manufacture and greatly reduces friction, the latter serving to render the clock mechanism more accurate.

45. What I claim as new is:

In a mechanism of the type set forth, a frame having a hole, forwardly-projecting spaced pins mounted on said frame around said hole, a ring-gear journaled on said pins 50 in front of said frame so as to surround said hole, this ring-gear carrying a minute-hand, a set of rearwardly-extending pins mounted on the frame around said hole, an hour-gear mounted rotatably upon these 55 rearwardly-extending pins so as to surround said hole in the frame, this hour-gear being provided with a supporting arm extending radially inwardly and through the hour-gear and the hole in the frame and having its forwardly-projecting end provided with an hour-hand lying in a plane adjacent to the aforesaid minute-hand.

In testimony whereof I hereunto affix my signature.

FRED R. KALCK.
